HOSE SPRAY HEAD

Thomas P. Newman, Geneva, Eugene W. Mar-
chand, Jr., Maywood, and Edward A. Fredrick-
son, Chicago, Ill., assignors to Crane Co., Chi-
cago, Ill., a corporation of Illinois

Application November 3, 1939, Serial No. 302,646

10 Claims. (Cl. 299—112)

This invention relates in general to a hose spray head and connection therefor. It is applicable to various types of hose sprays, nozzles and connections and has particular utility in conjunction with kitchen sink or the like spray heads which are used for washing or rinsing the sink or articles contained therein.

We are aware that there have been previous types of spray heads in which the latter have been made integrally of metal; therefore, this invention contemplates the provision of a spray head whereby the handle or grip portion of the head which, though rigidly secured to the spray nozzle, is of a separate piece or construction and is preferably, although not necessarily, insulated against the rapid conduction of heat to the handle by air spaces and passageways allowing for the circulation of air between the nozzle and the handle.

Another object of the invention is to provide an improved hose connection which furnishes a leak-proof and secure attachment of the spray head to the hose with a minimum number of parts, the latter being easily and quickly assembled.

Other provisions contemplated by the present invention include a handle portion of the spray head which provides a convenient and comfortable grip for the fingers of a user, a shank portion which prevents rotating or turning of the head when the latter is at rest in its socket, and a spray face portion which is readily removable for cleaning and inspection purposes.

The manner in which the invention is carried into effect and its more detailed nature and advantages may best be understood from a consideration of the ensuing portion of this specification, taken in conjunction with the accompanying drawing, in which a suitable form of apparatus is described principally by way of example.

In the drawing:

Fig. 1 is an exterior plan view of our improved spray head.

Fig. 2 is a vertical sectional view of the spray head showing the detailed construction thereof.

Fig. 3 is a sectional view taken on the line 3—3 of Fig. 2.

Fig. 4 is a sectional view taken on the line 4—4 of Fig. 2.

Similar reference numerals refer to similar parts throughout the figures.

Referring to the drawing, and in particular to Figs. 1 and 2, the spray head embodying our invention comprises the grip or handle 1 which may be of metal, wood, composition or the like, the nozzle casing or tube 2, the nut 3, and the sleeve 4. Support for the head is provided by the socket or bushing 5 which is secured to a sink wall 6 by the nut 7. Preferably a rubber

tube or hose 8 is provided for the water supply to the spray head and is connected to the inlet end 9 thereof, the other end of the tube 8 is connected to a suitable source of water supply (not shown) which, if desired, may be a back-board outlet on the sink faucet. The rubber tube 8 is preferably made sufficiently long to permit a person at the sink to grasp and to lift the head out of the socket 5, pull a portion of the tube through the socket and then to subsequently spray any portion of the sink or articles placed in the sink.

The nozzle casing 2 is formed with a substantially right angular bend in its middle portion 15 and an additional bend of about 45° near its outlet end 11. The inlet end 9 of the casing 2 is provided with a suitable means, such as the bulged portion 12, for resisting sliding movement of the hose 8 telescoped thereon, and the nut 3 is screwed onto the end of the hose to compress the latter against the casing 2 above the bulge 12 whereby the hose is securely connected to the nozzle in a leak-tight and slip-proof manner. A preferably rubber sleeve 4 having its upper end enclosed or shrouded by the handle 1 and its lower portion tapered is provided to enclose the hose and nozzle connection and to furnish an external gripping surface for the socket or bushing 5 to contact and to prevent the head from turning while the latter is positioned in the socket.

As more clearly shown in Figs. 3 and 4, the lower portion of the handle 1 is widened and recessed so that it forms a shroud or open-bottomed cover for the nozzle casing 2. The recess 13 in the lower portion of the handle conforms generally to the shape of the nozzle casing but for insulating purposes the recess is preferably made sufficiently large to allow an air space 14 between the casing and the recess. A plurality of ribs 15 are provided in the recess 13 for the relatively small contact areas between the casing and the handle.

Again referring to Fig. 2, we prefer to conceal 45 the attaching screw 16 within the outlet end 11 of the nozzle casing 2. In order to provide access to the screw 16 and for inspection and cleaning purposes, a cup-shaped spray face 17 is screw threadedly or otherwise removably secured to the end 11 of the casing 2.

The handle 1, because of being preferably made of wood, rubber, plastic or some other composition, has relatively poor heat conducting qualities. The upper or grip portion of the handle comprises a thin rib-like member having a rearwardly extending projection 18 beneath which a user's finger may be conveniently placed. Also, if desired, the grip portion may be provided either with an aperture or finger loop substantially as indicated by the dash lines 19. Of

course, the particular shape of this handle with respect to its exterior configuration is not significant, and may be changed to suit the type of installation.

While one form of the invention has been illustrated and described it is obvious that those skilled in the art may vary the details of construction as well as the precise arrangement of parts without departing from the spirit of the invention, and therefore it is not the desire to be limited to the above disclosure except as may be required by the appended claims, considering the state of the prior art.

We claim:

1. A spray head comprising a casing having an inlet and an outlet, the said inlet having connection to a suitable source of water supply, a spray face member secured to the said outlet, a handle for the said casing, the said handle having a lower overhanging portion and a finger grip portion, the said overhanging portion including a recess, ribs in the said recess and around a portion of the casing for the predetermined positioning of the said casing in spaced relation to the bottom of the said recess, whereby a clearance is provided between the said casing and the said handle, and means accessible through said outlet for assembly of said casing with said handle.

2. A spray head comprising a nozzle casing having an inlet and an outlet, the said inlet having connection to a suitable source of water supply, a spray face member detachably secured to the said outlet, a handle for the said casing, the said handle comprising respectively hollow and finger grip portions, the said hollow portion including a recess with means in the said recess providing for the predetermined positioning of the said casing in spaced relation to the said handle, and removable means within the interior of said casing providing for the said predetermined positioning within said recess portion of the handle.

3. A retractable spray head comprising an angular casing tube having an inlet and an outlet, a handle for the said tube, means for connecting the said inlet to a source of water supply, a sleeve surrounding the said tube inlet, the said handle forming a substantially unbroken connection with one end of the said sleeve, the other portion of the said latter member bearing against a portion of the said tube when in retracted position, the means connecting the handle with the said tube being accessible through the said outlet.

4. A spray head comprising a nozzle casing having an inlet and an outlet, the said inlet having connection to a suitable source of water supply, a spray face member detachably secured to the said outlet, a superposed handle having a lower recessed portion for reception of a portion of the said casing, means in engagement with the recessed portion of the handle for attachment of the said handle to the said casing, the said latter means being accessible upon removal of the said spray-face member.

5. A retractable spray head comprising an angular casing having an inlet and an outlet, a handle for the said casing mounted upon an upper surface thereof, means for connecting the said inlet to a source of water supply, a sleeve surrounding the said casing inlet, the said handle cooperating with the said sleeve and the said

nozzle casing to form a common connection therebetween, the said sleeve having an annular enlargement against which portions of the handle and the casing bear, the said annular enlargement serving as a stop when the spray head is retractably mounted in a suitable aperture.

6. A spray head comprising a casing having an inlet and an outlet in angular relation, the said inlet having connection to a suitable source of water supply, a spray face member detachably secured to the said outlet, an independent handle for the said casing, the said handle having a lower depending portion and a substantially upright finger grip portion, the said depending portion being recessed to accommodate the upper transversely angular portion between the said inlet and outlet of the said casing, the means for attachment of the said handle to the said casing being accessible from the interior of the said casing.

7. A spray head comprising a casing having an inlet and an outlet, the said inlet having connection to a suitable source of liquid supply, spray face means within the said outlet, a handle for the said casing, the said handle having a lower annular flanged portion and an upright grip means, the former including a recess, means within the said casing for attachment of the said handle to the said casing, the said means of attachment being removable through the outlet of the said casing.

8. A spray head comprising a tubular fitting of substantially L-form having an inlet and an outlet, a handle for the said fitting, means for connecting the said inlet to a source of water supply, the said handle cooperating with the said fitting to substantially contain an angular portion of the latter member, means positioned within the said fitting and extending through a wall thereof for attachment of the said handle to the said fitting, the said means being accessible through the said outlet.

9. A spray head comprising a nozzle casing having an inlet and an outlet, a handle for the said casing, means for connecting the said inlet to a source of water supply, a tapered sleeve surrounding the said casing inlet, connecting means removable through said outlet and disposed between the said handle and the interior of the said nozzle casing to form a common connection between upper portions of the said casing and the underside of the said handle, the said sleeve having an enlarged annular end portion shouldered against underside portions of the said casing and the said handle.

10. A spray head comprising an angularly formed nozzle casing having an inlet and an outlet, a demountable handle for the said nozzle casing, means for connecting the said inlet to a source of water supply, the upper portion of the said handle being flattened and extending vertically in a direction substantially parallel to the central axis of the said inlet, the lower portion of the said handle having an annular enlargement extending transversely to the upper portion thereof and having recessed means serving to shield and to surround an outer upper portion of the said inlet and outlet of the said casing.

THOMAS P. NEWMAN.
